(57) **CLAIM**

The ornamental design for a front spoiler, as shown and described.

DESCRIPTION

FIG. 1 is a front perspective view of an automobile to which a front spoiler in accordance with the design is attached;

FIG. 2 is a front view of the front spoiler in accordance with the design;

FIG. 3 is a top plan view of the front spoiler in accordance with the design;

FIG. 4 is a right side view of the front spoiler in accordance with the design (the left side is a mirror image);

FIG. 5 is a rear view of the front spoiler in accordance with the invention; and,

FIG. 6 is a bottom plan view of the front spoiler in accordance with the design.

It should be understood that the automobile shown in broken lines in FIG. 1 is for illustration only, and does not form part of the claimed design.
